UNITED STATES PATENT OFFICE

2,142,277

DEVICE FOR TURNING AND EDGE-STITCHING ROUND-CORNERED CUFFS

John I. McDonald, St. Joseph, Mo.

Application May 20, 1935, Serial No. 22,477

8 Claims. (Cl. 112—153)

My invention relates to a device for turning and edge-stitching round cornered cuffs.

Most cuffs for men's shirts are made according to the "run up and turn" method, which consists of using two blanks of cloth and stitching them together near one edge, the pieces of cloth being held with their outer sides together. This original stitching forms the shape of the outer edge of a cuff, and the border portion between the 10 stitching and the edge of the material is subsequently to be turned in and stitched again by the stitching which forms the edge-stitching of a finished cuff. In the past, this process has required considerable skill in order to make a finished cuff neat in appearance.

By the use of my invention, I am able to take a cuff which has been originally "run up" and turned outside out by an operator, and hold the cuff in position to be finally edge-stitched either 20 in a straight line or in a curved line. The present form of cuff commonly in use is one which will require that a curved portion be stitched first, then a straight portion, and finally another curved portion.

25 While this is the normal stitching cycle desired, (that is, curve—straight—curve) it will be possible with my device to start with either a curve or a straight portion.

In the past, it has been necessary to turn the 30 cuff after the original stitching is finished and to crimp the edges thereof sufficiently to hold the marginal edge of the cuff in proper position to be finally edge-stitched.

By the use of my device, this marginal portion 35 is properly held in position within the cuff as it is finally edge-stitched in one process.

An object of my invention is to provide a device for completing the turning of a cuff and presenting the cuff to the needle of a sewing-machine 40 in position to be edge-stitched, the turning of the cuff to be simultaneous with the stitching operation.

A further object of my device is to provide 45 means for holding a cuff to be edge-stitched either in a curved or a straight line.

A further object of my invention is to provide 50 means which will hold a cuff to be edge-stitched and properly position the marginal portion between the two outer layers of a cuff so that the finished product will be smooth on both sides.

In the drawings:

Fig. 1 is a perspective view of my device and a portion of a conventional sewing-machine;

Fig. 2 is a plan view;

Fig. 3 is a plan view of a portion of my device with the top guide blade removed;

Fig. 4 is a longitudinal cross-section on the line 4—4 of Fig. 3;

Fig. 5 is an enlarged cross-section on the line 5—5 of Fig. 4; and

Fig. 6 is a disassembled perspective view of the two sets of guide-blades.

I utilize a conventional sewing-machine, which has either one needle as shown in the drawings, 10 or which may have two or more needles, the number of needles being dependent on the type of edge-stitching which it is desired to produce. The top-plate 2 of the sewing machine is mounted on the table 4 to which I attach my cuff guiding 15 device as shown in Figs. 1 and 2.

I provide a base 6 which is adapted to be fastened by means of countersunk screws 8 or any other suitable means to the table 4. The purpose of the plate 6 is to raise the other portions of 20 my device so that they will be in proper alignment with the needle and presser-foot 3 of the sewing-machine.

I provide an elliptical plate 10 which is slidably secured to the base 6 by means of counter- 25 sunk screws 12 in the slots 14.

A T-shaped arm 16 is pivotally secured to the elliptical plate 10 by means of the pivot 18. A stop 20 is upstanding from the adjustable plate 10 in position to form a stop for the T-shaped 30 arm 16 when the arm is in its proper operative position.

On the part of the T-shaped arm 16 remote from the pivot 18, I provide a U-shaped channel 22, which channel is adapted to hold and guide 35 the cuff guide members, which will be described hereinafter. The U-shaped channel 22 is riveted or secured in any suitable manner to the portion of the T-shaped arm 16 remote from the pivot 18.

The cuff guiding plates 24 and 24' constitute 40 one pair, and are provided with curved outer extremities 26. The cuff guiding plates 28 and 28' constitute a second pair and are provided with straight extremities 30 at right-angles to the edges of the plates 24 and 24'.

The cuff guiding plates 24 and 24' are spaced 45 apart and secured together by means of the rack-bar 32 which is held between the cuff guiding plates by suitable rivets, bolts, or by welding or any other means on one side thereof at the end 50 remote from the curved extremities 26.

The cuff guiding plates 28 and 28' are likewise spaced apart and are secured together by means of the rack-bar 34, which is likewise positioned on one side of the guide plates 28 and 28' at the 55

end thereof remote from the straight extremities 30.

The pair of guide plates 28 and 28' are adapted to be positioned between the blades 24 and 5 24' of the other pair of cuff guiding plates.

When these two pairs of cuff guiding plates are assembled, as shown more particularly in Figs. 3, 4 and 5, the rack-bars 32 and 34 will assume the positions shown in Fig. 3 and the curved extremities 26 of the guide plates 24 and 24' will be in an extended position, the straight extremities 30 of the guide plates 28 and 28' being in a retracted position. While these pairs of guide plates 24 and 24' and 28 and 28' are in their 10 assembled position, a pinion-gear 36 is placed between the two rack-bars and is held in position by a suitable bolt 38 being passed therethrough from under the T-shaped arm 16, through the U-shaped channel 22, the pinion 36, and a slot 40 15 in the guide-plate 24.

After the bolt 38 has been placed in position, a knurled handle 42 is placed over the end thereof and is secured thereto by a set-screw or any other suitable means. The knurled knob 42 is 20 provided with a flared base 44, which is sufficiently large in diameter to extend over the edges of the slot 40, thereby holding the guide plates in their assembled position.

On the sewing-machine I provide a substantially L-shaped flange 46 in alignment with the needle and presser-foot 3 of the sewing-machine. This L-shaped flange 46 is adapted to provide an abutment against which the guide-plates 24-24', 28-28' hold the cuff while it is being 25 edge-stitched.

In preparing a cuff to be edge-stitched, the cuff is first stitched along the edge, while the outer sides of the finished cuff are together. When it is desired to complete the edge-stitching, 30 the operator turns the cuff outside out and places the entering portion of the cuff over the guide plates 24-24' (it being understood that generally a curved edge is to be stitched first, as recited above).

45 The marginal portion of the cuff between the edge thereof and the original stitching extends between the guide plates 24-24' while the other portion of the cuff is held back over the outside of these guide plates. In this manner the marginal edge of the cuff is held smooth and in proper position within the outer pieces of material which are to form the cuff, and the material is at the same time held by the guide plates 24-24' in position against the L-shaped flange 46 and in the path of the needle of the sewing-machine.

As the stitching is done, the cuff will be guided around a curved portion, a straight portion, and a curved portion, as will be more fully described 60 hereinafter.

For the purpose of further explanation, let it be assumed that a curved portion of the cuff is being edge-stitched. While the curved portion is being edge-stitched, the device will be in the 65 position shown in the drawings with the guide plates 24-24' in their extended position so that the curved extremities 26 will guide the cuff to the sewing-machine needle.

After the curved portion of the cuff has been 70 stitched and it is desired to stitch the straight edge of the cuff, the knurled knob 42 is turned in a counterclockwise direction, whereby the rack-gear 36 is turned and the rack-bar 32 is moved to the left, retracting the guideplates 24-24'. At the same time, the rackbar 34 is

moved to the right, and the guide-plates 28-28' are extended into the position in which the guide-plates 24-24' have been, the straight extremities 30 holding the cuff against the L-shaped flange 46 and in position to be stitched by the machine. 5 After the straight edge has been stitched, and it is necessary again to stitch a curved edge, the knurled handle 42 is turned in a clockwise direction and the guide-plates 28-28' are retracted as the guide-plates 24-24' are extended to hold 10 the cuff while it is being edge-stitched around a curve.

To retract and extend the guide-plates 24-24' and 28-28', it will be necessary only to turn the knurled handle 42 through approximately one 15 hundred and twenty (120°) degrees, which turn, of course, takes only a fraction of a second, and, therefore, it is not necessary to stop the sewing-machine while the straight edge guide plates are being substituted for the curved edge guide plates, 20 or vice versa, the cuff being held in position to be stitched at all times.

After the cuff has been completely edge-stitched, the guide-plates are swung away from the sewing-machine by turning the T-shaped arm 25 16 on the pivot pin 18. While the guide-plates are in this position, a new unfinished cuff may be placed over the edges 26 or 30 of the guide-plates 24-24' or 28-28', after which the T-shaped arm 16 and its associated mechanism may 30 be swung back until it abuts against the stop 28 and the cuff is in position to be edge-stitched as described above.

While I have disclosed and described a simple and very satisfactory form which my device has 35 taken, it will be understood that many minor changes, for example in the position of the rack-bars and the guide means, may be made without departing from the spirit of the invention. Also it is to be understood that while I have 40 shown a single needle sewing-machine, my positioning device may be utilized on any sewing-machine, such as one having two or more needles positioned to make two or more lines of stitching.

45 I claim:

1. In a device for guiding cuffs to be edge-stitched, an arm pivotally secured to a base plate, a substantially U-shaped channel member secured to said arm, and guide plates slidably within said U-shaped channel member, said guide plates being adjustable to align with the needle of a sewing-machine.

2. In a device of the character described, an arm pivotally secured to a base plate, a U-shaped channel secured to said arm, two pairs of guide plates slidably within said channel member, and means for sliding said guide plates.

3. In a device of the character described, an arm pivotally secured to a base plate, a U-shaped channel member secured to said arm at the end thereof remote from said pivotal connection, two pairs of guide plates slidably secured within said channel member, and means for sliding one pair of said guide plates in one direction while sliding 60 the other pair in the opposite direction.

4. In an edge-stitching device, the combination of an arm connected with a base plate, a pair of guide plates slidably secured to said arm, a second pair of guide plates slidably secured to 70 said arm and within said first-mentioned pair of guide plates, and means for moving said pairs of guide plates simultaneously in opposite directions.

5. In an edge-stitching device, the combination of an arm pivotally secured to a base, a sub- 75

stantially U-shaped channel member secured to said arm, a pair of guide plates slidably secured in said channel member, a pair of guide plates slidable within the first-mentioned pair of guide plates, means for moving said pairs of guide plates relative to one another, and means cooperating with said guide plates for holding material to be edge-stitched.

6. In an edge-stitching device, the combination 10 of an arm pivotally secured to a base, a substantially U-shaped channel member secured to said arm, a pair of guide plates slidably secured in said channel member, a pair of guide plates slid- 15 able within the first-mentioned pair of guide plates, means for moving said pairs of guide plates relative to one another, means cooperating with said guide plates for holding material to be edge-stitched, one pair of said guide plates hav-

ing curved ends, the other pair having straight ends.

7. In an edge-stitching device, the combination 5 of two pairs of guide plates, one pair of said guide plates being slidable within the other pair, and rack and pinion means for sliding the said pairs of guide plates and holding them in guid- ing position.

8. In an edge-stitching device, the combination 10 of two pairs of guide plates, one pair of said guide plates spaced apart by a rack bar, and the other pair of guide plates spaced apart by a rack bar and interposed between the plates of the first-mentioned pair of guide plates and pinion means 15 engaging said rack bars for moving said pairs of guide plates simultaneously in opposite directions.

JOHN I. McDONALD.
